UNITED STATES PATENT OFFICE

CARL SCHWARTZ, OF ELKHART LAKE, WISCONSIN, ASSIGNOR TO BRANDT AUTOMATIC CASHIER COMPANY, OF WATERTOWN, WISCONSIN, A CORPORATION OF WISCONSIN

COIN COUNTING MACHINE

Application filed April 9, 1926. Serial No. 100,859.

This invention relates to coin counting machines.

Coin counting machines have been heretofore made, but they did not give perfect satisfaction for a number of reasons, among which may be mentioned the fact that sticking frequently occurred so that the machine was not certain in its action, and also the absolute accuracy required of these machines was not always attained. For example, when electrical contact was made by the passing coins, it was found that these machines frequently skipped a count, and consequently, could not be relied upon.

Objects of this invention are to provide a coin counting machine which is absolutely accurate in its operation, which may be associated with a coin separator to receive the coins directly therefrom, which does not employ any electrical contacts whatsoever, but instead, utilizes mechanical operations for positively actuating the counters.

Further objects are to provide a novel form of coin counting machine in which energy is mechanically imparted to the coin so that it can exert sufficient force to insure the operation of the coin counter, and in which all possibility of sticking or improper actuation of the counter is avoided.

Further objects are to provide a simple type of coin counting machine which may be operated without any thought on the part of the operator, and which is free from fragile or delicate parts.

An embodiment of the invention is shown in the accompanying drawings, in which:

Figure 1 is a sectional view through a portion of the counting machine.

Figure 2 is a front view of the apparatus with parts broken away to more clearly show the construction.

Figure 3 is a sectional view approximately on the line 3—3 of Figures 1 and 2.

Figure 4 is a fragmentary detail of one of the counter arms and the adjacent portion of the actuator.

Referring to the drawings, it will be seen that the coin counting machine associated directly with a coin sorting machine, such as that disclosed in my patent No. 1,526,762 for

coin sorting machine, issued Feb. 17, 1925, is indicated generally by the reference character 1, and the coin counting machine is attached directly thereto. For example, the coin counting machine may have a plate 2 secured to the under side of the coin sorting machine. This plate is provided with a plurality of channels 3 into which coins of the appropriate denomination are passed. The coins pass through the chutes 3 into the vertical chutes 4 and are discharged into the appropriate hoppers or receiving compartments 5. Preferably, a spring finger 6 is positioned in each of the coin chutes 3 to prevent the coins from jumping upwardly as they pass the mechanism for forcing them past the counters, such mechanism to be hereinafter described in greater detail.

Further, it is preferable to provide spring fingers 7 projecting slightly across the lower ends of the delivery chutes 4 so as to turn the coins and cause them to fall flatly into the hoppers.

It is to be noted, particularly from Figures 1 and 3, that the plate 2 is slotted to receive the ribs 8 of an actuating or driving roller 9. This roller is mounted upon a transverse shaft 10 as shown in Figures 1 and 2, and is preferably provided with a pulley 11 belted to an electric motor or other suitable driving means such as indicated at 12. The ribs 8 are preferably formed of rubber or other yielding material and project slightly through the plate 2 beneath each of the channels 3. These ribs are adapted to engage the coins as they pass through the chutes 3, one of the coins being indicated in Figure 4 by the reference character 13. Immediately above the plate 2 and adjacent the apertures therethrough are pivoted a plurality of levers or actuators which are provided with a coin contacting arm 14—See Figure 1—and with an upper arm 15. The upper arm, preferably, carries a spring 16 at its outer end adapted to contact with the roller 17 of the counter arm 18. This counter arm in each instance is clamped upon the counter shaft 19. Conventional types of counters, such as indicated at 20, may be employed, and as previously described, their

operating arms are actuated by the lever 15 through the medium of the spring 16, such spring affording the requisite yield to prevent binding or other damage to the counter 5 arm. These levers or actuators are each mounted upon a transverse shaft 21, and one of each of the levers or actuators is associated with each of the channels 3. A transverse rod 22 is positioned beneath the arms 10 15 of these actuators and affords a rest therefor.

Each of the counters 20 is provided with a clearing lever or arm 23. Each of these arms carries a pin 24. Means are provided 15 for simultaneously clearing the counters, and such means may comprise a transverse slide 25 provided with a plurality of notches 26 adapted for the reception of the pins 24 as shown most clearly in Figures 2 and 3. This 20 slide 25 is guided in the side frames 27 of the coin counting machine. It is preferably provided with rack teeth 28 which engage the segmental gear 29. This segmental gear is provided with an upwardly projecting lever 25 30 equipped with a handle 31. Thus, when the handle 31 is manipulated, the counters are simultaneously cleared, and the machine is in condition for a further cycle of operations.

30 The operation of the machine is as follows: Assuming that the coin sorting machine is in active operation, it will be seen that the coins are fed downwardly to their appropriate passages or channels 3. They pass 35 downwardly along these channels to a position beneath their appropriate levers 14 as shown in Figure 1. At this point, the coin has additional energy supplied thereto by means of the roller or drum 9 whose projecting ribs 8 frictionally engage the lower edge of the coins and move them beneath the levers 14, thus raising such levers. The arm or lever 15 is accordingly raised as it is integral with the lever 14, and through the 40 45 medium of the spring 16, positively actuates the counter arm 18.

It is to be noted particularly that the momentum of the downwardly passing coin is not relied upon to operate the actuator, and 50 consequently, the counters, but additional energy is imparted to the coins by means of the transverse roller so that the coins are positively passed beneath the levers 14 in a mechanical and certain manner.

55 Certain of the chutes or passageways 3 may be provided with springs such as indicated at 3' in Figure 2 to insure the vertical positioning of the coin. For example, in the dime chute or channel, a spring has been 60 shown as positioned upon the side of the channel and projecting slightly there into. This spring keeps the coin from tilting, although the coin may be extremely thin.

It is to be noted also that the guards 6 prevent the coins from jumping upwardly as

they pass the roller, and consequently, guide the coins into the chutes 4.

It will thus be seen that a positive and reliable count of the coins is assured by this 70 machine.

As a matter of actual fact, these machines have been tried and have been found to give absolute accuracy in the counting of the coins.

Although the invention has been described in considerable detail, such description is intended as illustrative rather than limiting as the invention may be variously embodied and as the scope of such invention is to be determined as claimed. 75

I claim:

1. In a coin counting machine, the combination with a member having a chute through which coins may be passed, a bell crank lever pivoted above said chute and having a first arm extending into, and partially obstructing, the chute, means to carry said coin past said first arm, a second arm having a spring on the end thereof, and a counter adapted to be operated from said spring. 80

2. In a coin counting machine, the combination of a member having a chute through which coins may be passed, a bell crank lever fulcrumed to be rocked in the plane of said chute, said lever comprising a first and a second arm, said first arm being maintained 90 partially in the chute by gravity, a spring fixed to the end of said second arm, a counter adapted to be actuated from said spring, and means to carry said coin past said first arm. 95

3. In a coin counting machine, the combination of a member having a chute through which coins may be passed, an actuator comprising a lever having forked arms and pivotally suspended above said chute to swing therewithin, means above said chute restraining the swinging movement of said actuator to dispose only one of said arms within the chute, a spring member on the other said arm and a counter operated by said spring. 100

4. In a coin counting machine, the combination of a member having a chute through which coins may be passed in upright vertical position, an actuator comprising a bell-crank lever pivoted above said chute to project one of its arms into the chute by gravity 105 and form an inclined top partially closing the same and extending into the path of coins being passed through the chute, a counter adapted to be operated by the other arm of the bell-crank, and power means forming the 110 bottom of the chute beneath the bell-crank lever for forcing the coins past the bell-crank lever to lift the same and actuate the counter.

5. In a coin counting machine, the combination of a member having a chute through which coins may be passed in upright vertical position, an actuator comprising a bell-crank lever pivoted above said chute to project one of its arms into the chute by gravity 115

and form an inclined top partially closing the same and extending into the path of coins being passed through the chute, a counter adapted to be operated by the other arm 5 of the bell-crank, and resilient means interposed between said other arm of the bell-crank and the counter.

6. In a coin counting machine, the combination of a member having a chute through 10 which coins may be passed in upright vertical position, an actuator comprising a bell-crank lever and pivoted above said chute to project one of its arms into the chute by gravity and form an inclined top partially closing the 15 same and extending into the path of coins being passed through the chute, a counter adapted to be operated by the other arm of the bell-crank, a flexible spring element carried by said other arm of the bell-crank and 20 engageable with a counter carried part, and power means forming the bottom of the chute beneath the bell-crank lever for forcing the coins past the bell-crank lever to lift the same and actuate the counter, said spring 25 element providing a yielding connection between the bell-crank lever and the counter carried part.

In testimony that I claim the foregoing I have hereunto set my hand at Elkhart 30 Lake, in the county of Sheboygan, and State of Wisconsin.

CARL SCHWARTZ.
